UNITED STATES PATENT OFFICE.

HENRY ZIEGLER, OF NEW YORK, N. Y.

MUSIC-RACK ATTACHMENT FOR UPRIGHT PIANOS.

SPECIFICATION forming part of Letters Patent No. 378,486, dated February 28, 1888.

Application filed July 27, 1887. Serial No. 245,412. (No model.)

To all whom it may concern:

Be it known that I, HENRY ZIEGLER, of the city, county, and State of New York, have invented certain new and useful Improvements 5 in Music-Rack Attachments to Pianos, of which the following is a specification.

This invention relates to a music-rack for upright pianos, by which the same can be readily changed from a panel to music-rack 10 and back to a panel, as required; and the invention consists of a panel hinged to the front of the piano-case, said panel being provided at the lower end with a ledge for supporting the music, said ledge being guided by a center 15 bracket and corner pieces of the panel and acted upon by a spring. For closing the panel, the ledge is forced in and retained by a suitable locking device, which is released when opening the panel and changes it into a rack 20 by means of a suitable push-button or other releasing device.

In the accompanying drawings, Figure 1 represents a front view of the upper part of an upright piano with my improved music-rack 25 attachment. Fig. 2 is a rear elevation, drawn on a larger scale, of the movable panel of the music-rack and its locking devices; and Figs. 3 and 4 are vertical transverse sections of the same on line $\alpha\alpha$, Fig. 1, showing it, respectively, in open and closed position.

Similar letters of reference indicate corresponding parts.

In the drawings, A represents a panel, which is hinged in any suitable manner at its upper 35 edge to the front of an upright-piano case. At the lower edge of the panel is arranged a sliding ledge, B, which is equal in length with the panel and guided on the same by a grooved central guide-bracket, a, which engages a fixed 40 tongued or dovetailed rail, b, of the ledge B. The sliding ledge B is further guided by its recessed ends in corner guide-pieces, d d, of the panel B, as shown in Fig. 2, so as to produce the even and steady motion of the sliding 45 ledge B at the lower edge of the panel A. A strong band-spring, C, that is attached to a bracket at the rear of the panel A, presses on a projecting portion, e, of the sliding ledge B, so as to move the latter forward when the 50 panel is in open position. At the under side of the sliding ledge B is arranged a catch, f,

which is engaged by the hook-shaped end of a fulcrumed and spring-actuated lever, f', of the piano-case, the lower arm of said lever being acted upon by a sliding button, f'', which is 55 located at the front part of the upright-piano case centrally below the panel A, and the shank of which is provided with a stop-pin, f''. When the panel A is in closed position, the catch f of the sliding ledge B is engaged by the locking- 60 lever f', so that the front end of the ledge B is flush with the molding of the panel A, and closes thereby the opening in the front of the piano-case, as shown in Fig. 4.

For releasing the panel and changing it into 65 a music-rack, the button f'' is depressed, so that the locking-lever is released from the catch of the ledge, which permits the forward motion of the ledge B by the action of the spring C and the forward swinging of the entire panel, 70 so that the lid of the piano can be placed below the same for holding it in inclined position and receiving the music, as shown in Fig. 4.

The pressure of the spring C supports the 75 ledge B when in forward position, as shown in Fig. 3. For returning the panel into closed position, the lid is first closed, the panel returned into the opening of the case, and the ledge then pressed inwardly until it is engaged by the locking device, which holds the ledge 80 and panel in closed position.

The hinged panel, sliding ledge, and the locking and releasing devices for the latter form a neat and readily-operated music-rack attachment for upright pianos, that can be 85 quickly and easily placed in position for supporting the music or closed up so as to form a panel of the case.

Having thus described my invention, I claim as new and desire to secure by Letters Patent— 90

1. The combination of a panel hinged to the front of a piano-case, a sliding and spring-actuated ledge guided at the lower end of said panel, means for locking the ledge and panel in closed position, and means for releasing said 95 ledge and panel, substantially as set forth.

2. The combination of a panel hinged at its upper end to the front of a piano-case, a sliding ledge guided at the lower end of said panel, and a spring attached to the panel and pressing 100 on the ledge for holding the same in forward position, substantially as set forth.

3. The combination of a panel hinged at its upper end to the front of a piano-case and provided with a center bracket and corner guide-pieces, a sliding ledge having a fixed rail guided in said center bracket, a spring attached to the panel and acting on the rear end of the sliding ledge, a catch at the under side of the ledge, a fulcrum and spring-actuated locking-lever, and a button for releasing said locking-lever

from the catch of the ledge, substantially as set forth.

In testimony that I claim the foregoing as my invention I have signed my name in presence of two subscribing witnesses.

HENRY ZIEGLER.
